United States Patent Office.

JAMES A. DUNWORTH AND FRANK DUNWORTH, OF NEW YORK, ASSIGNEES
TO "VIDWARD & SHEEHAN," OF UTICA, NEW YORK.

Design No. 4,625, dated February 7, 1871.

DESIGN FOR A LIQUOR-HOLDER.

The Schedule referred to in these Letters Patent and making part of the same.

We, JAMES A. DUNWORTH and FRANK DUNWORTH, of the city, county, and State of New York, and comprising the firm of J. A. & F. Dunworth, and doing business at No. 99, 101, 103, East Houston street, in the city of New York, in the State of New York, have invented and produced a new and original Design for Holding Liquor, and to be called the Spirit-Harp, of which the following is a specification.

The nature of our design is fully represented in the accompanying photographic illustration, to which reference is made.

A is the base;

B, the tube for holding the liquor;

C, the cover;

D, the cock for drawing off the liquor;

E E, the screws, where the arms of the harp are screwed on;

F, the upper arm; and

G, the lower arm for holding the wires.

H, the wires for ornament; and the whole arranged substantially as and for the purpose herein set forth.

We claim as our invention—

The design for holding liquor, as shown.

JAMES A. DUNWORTH.
FRANK DUNWORTH.
